WIRE REEL

Robert L. Atkinson, 1110 Custom Way,
Springfield, Oreg. 97477
Filed Aug. 3, 1965, Ser. No. 476,935
7 Claims. (Cl. 242—106)

This invention relates to wire reels, and more particularly to a wire reel especially constructed and arranged for use by electricians and the like for unreeling a purchased spool of wire during the wiring of a building or other similar uses.

When electricians wire a partially constructed building, they customarily utilize reels or spools of wire that are purchased from a wiring manufacturer. Ordinarily, the purchased spool of wire is placed on the floor of a building and the wire is allowed to unspool when unreeled by the person installing it. This customarily leads to a tangled mass of wire on the floor of the construction area and produces a plurality of tight loops or kinks which must be straightened out prior to securing to a wall, beam, ceiling or the like. It will be seen therefore, that considerable unnecessary time and effort is spent by electricians or their helpers in straightening out or removing tight loops and kinks during such an installation.

It is accordingly a primary object of the instant invention to provide a wire reel which may be readily moved from place to place and is arranged to accommodate a conventional spool of wire or the like.

Another object of the instant invention is to provide a wire reel having a first axis of rotation about which a spool of wire may be placed and a second substantially perpendicular axis of rotation to allow for movement of the electrician or wirer without requiring the repositioning of the wire reel.

A further object of the instant invention is to provide a wire reel having a pair of upstanding flanges for constraining the sides of a spool of purchased wire with one of these flanges being removably mounted to provide for the convenient and rapid positioning of the purchased spool of wire on the wire reel of the instant invention.

A still further object of the instant invention is to provide means for temporarily securing the wire reel of the instant invention to a fixed member, such as an overhead beam.

A more specific object of the instant invention is to provide an inverted substantially J-shaped attachment means by which the wire reel of the instant invention may be readily placed and removed from an overhanging beam or the like.

Still another object of the instant invention is to provide a wire reel which is inexpensively manufactured, which is long lasting and which requires no maintenance.

Other objects and advantages of the instant invention reside in the combinations of elements, arrangements of parts, and features of construction and operation, all as will be more fully pointed out hereinafter and disclosed in the accompanying drawing wherein there is shown a preferred embodiment of this inventive concept.

In the drawing:

FIGURE 1 is a side elevational view of the wire reel of the instant invention temporarily secured on a horizontal beam represented in dotted lines;

FIGURE 2 is a front elevational view of the device of FIGURE 1 illustrating a spool of wire secured thereon; and

FIGURE 3 is an exploded cross-sectional view taken

2

along line 3—3 of FIGURE 2 emphasizing the removable nature of one of the flanges of the wire reel of the instant invention.

Referring now to the drawing in detail wherein like reference characters designate like elements throughout the several views thereof, there is indicated generally at 10 a wire reel having as its major components a spool receiving means shown generally at 12 receiving a spool of wire 14, a first mounting means indicated generally at 16 mounting spool receiving means 12 about a first axis and a second mounting means designated generally at 18 mounting first mounting means 16 about a substantially perpendicular axis and temporarily securing wire reel 10 to a horizontal beam 20.

Spool receiving means 12 includes a preferably hollow central hub 22, which may be of any convenient configuration, but which is preferably substantially cylindrical, adjacent a first flange 24 which extends substantially beyond the periphery of hub 22. First flange 24 is preferably a thin circular plate carrying a pair of substantially perpendicular bolts 26, 28 threaded on the free end thereof as at 30, 32 with threaded portions 30, 32 extending beyond the end of central hub 22. Central hub 22 includes an end portion 34 having an enlarged central indentation 36 communicating with a coaxial opening 38 for purposes more fully explained hereinafter.

First mounting means 16 includes a bolt 40 extending through a central opening 42 in flange 24 and is provided with a nut 44 or other similar securing means residing in indentation 36 of end portion 34. A washer 46 is positioned on the outer side of flange 24 and spaces a pair of circular collars 48, 50 away from flange 24. It should be seen that the construction of first mounting means 16 secures hub 22 to flange 24 and also allows the rotation of hub 22 and flange 24 with respect to bolt or axle 40.

The remainder of spool receiving means 12 includes a flange 52 of similar configuration to flange 24 providing a pair of apertures 54, 56 spaced to receive the threaded portions 30, 32 of bolts 26, 28. Second flange 52 is secured to bolts 26, 28 by a pair of wing nuts 58, 60. It will be seen that second flange 52 is removably mounted with respect to central hub 22 such that a purchased spool of wire may be easily and rapidly placed on hub 22 in preparation for the wiring of a building or the like.

Second mounting means 18 includes a first mounting member shown generally at 62 providing a substantially straight portion 64 to which is perpendicularly secured an apertured member 66. Secured to straight section 64 away from apertured member 66 is an S-shaped member 68 having a straight portion 70 on the end thereof received between circular flanges 48, 50 of first mounting means 14. It will be seen that the provision of S-shaped portion 68 results in the entirety of second mounting means 18 being positioned away from and out of interference with wire 14 as it may be unspooled.

Second mounting means 18 includes a second mounting member shown generally at 72 providing a first straight section 74 at the upper end of which is secured a straight section 76 carrying a perpendicular member 78 parallel to and of lesser extent than first straight member 74 forming an inverted substantially J-shaped attachment means receiving horizontal beam 20 therein. Second mounting means 72 includes a second perpendicular straight section 79 forming an aperture therein. The apertures of sections 66, 79 of first and second mounting members 62, 72 are aligned by a bolt 80 receiving a pair of threaded nuts 82 on the end thereof. It will be seen that bolt 80 acts

as a pivot connection between first and second mounting members 62, 72 and is substantially perpendicular with respect to axle 40 of first mounting means 16.

In the use of wire reel 10, an electrician or the like may remove second flange 52 by unthreading wing nuts 58, 60 and may place a purchased spool of wire about central hub 22. Second flange 52 is then re-attached to central hub 22 and wire reel 10 is temporarily affixed to a beam or the like 20 allowing the workman to withdraw suitable amounts of wire 14 from spool receiving portion 12 with flanges 24, 52 and hub 22 undergoing the necessary rotation about axle 40 of first mounting means 16.

When the electrician finds it necessary to move about the construction area, which is something that cannot be avoided, a slight pull on wire 14 will rotate first mounting member 62 with respect to second mounting member 72 such that wire reel 10 need not be repositioned when the electrician works about the interior of a partially constructed room.

When the previously used spool of wire is exhausted, it is necessary only to remove second flange 52 and insert a new spool after which the wiring operation may be completed. If it is necessary to move from one room to another, the attachment means formed by second mounting member 72 may be removed from the overhead beam and taken to the new work area and positioned in a similar location.

It is apparent that wire reel 10 may be constructed of any desirable material, such as metal, plastic or any other suitable material.

It is now seen that there is herein provided an improved wire reel having all of the advantages of the instant invention and others, including many advantages of great practical utility and commercial importance.

Since many embodiments may be made of the instant inventive concept, and since many modifications may be made of the embodiment hereinbefore shown and described, it is understood that the foregoing description is to be interpreted merely as illustrative and not in a limiting sense.

I claim:

1. A wire reel comprising a hub about which a wire may be wound including two ends, a periphery, and a central axis, a pair of flanges, one of said flanges secured to said hub adjacent one end thereof and another of said flanges secured to said hub adjacent the other end, said flanges extending beyond said periphery of said hub, first mounting means mounting said hub for rotation about said central axis, second mounting means mounting said first mounting means for universal rotation about an axis at an angle to said central axis, said second mounting means providing temporary attachment means for loosely securing said second mounting means to a fixed member.
2. A wire reel comprising a hub about which a wire may be wound including a first end, a second end, a periphery and a central axis, said hub being symmetrical about said axis, a first flange secured adjacent said first end of said hub and extending beyond said periphery of said hub, a second flange secured adjacent said second end of said hub and extending beyond said periphery of said hub, first mounting means mounting said hub and said flanges for rotation about said central axis, said first mounting means extending through said first flange providing an extension, and second mounting means mounting said extension of said first mounting means for universal rotation about an axis substantially perpendicular to said central axis, said second mounting means providing

10

5 temporary attachment means for loosely securing said second mounting means to a fixed member.

3. The structure of claim 2 wherein said second mounting lies wholly to one side of an extension of said first flange.

4. The structure of claim 2 including means removably mounting said second flange on said hub.

5. The structure of claim 2 wherein said temporary attachment means includes an inverted substantially J-shaped member.

6. A wire reel comprising a substantially cylindrical hub about which a wire may be wound including two ends, a periphery and a central axis, a first substantially circular flange fixedly perpendicularly carrying one end of said hub at the center of said flange, said first flange extending substantially beyond said periphery of said hub, at least one threaded bolt extending substantially parallel with respect to said axis of said cylindrical hub beyond said second end, a second substantially circular flange providing at least one aperture receiving said threaded bolt, at least one wing nut secured on said threaded bolt fixing said second flange to said hub, first mounting means including an axle coaxial with said axis of said hub mounting said hub for rotation about said central axis, said axle extending through said first mounting means and second mounting means including a first mounting member secured to said axle of said first mounting means, a second mounting member providing an inverted substantially J-shaped attachment member providing means for temporarily securing said second mounting member to a fixed member and means pivotally mounting said first mounting member on said second mounting member substantially perpendicular to said axle of said first mounting means for universal relative rotation therebetween.

7. The invention of claim 1 wherein:

the hub comprises,

a cylindrical member, and
an end closure having a central indent and a central aperture closing one end of the cylindrical member;

the pair of flanges comprises,

a first flange having a central aperture and additional apertures adjacent the central aperture fixedly secured to the other end of the cylindrical member, and

a second flange having apertures corresponding to the additional apertures in said first flange; said hub further comprising,

at least two bolts extending through said additional apertures in said first flange and the apertures in the second flange securing said second flange to one end of the cylindrical member;

said first mounting means comprises,

an axle extending coaxially with the cylindrical member through the central apertures in the first flange and the end closure rotatably supporting said hub,

means on one end of the axle disposed in the central indent in the closure member securing said axle in said hub,

a pair of collar means on the other end of the axle for receiving the second mounting means, and means proximate the other end of the axle for spacing said second mounting means from said hub; and

said second mounting means comprises,

an elongate member secured to the other end of the axle at one end and having a universal pivotal portion at the other,

a hook member for suspending said reel vertically from an overhead member, said hook member being in the configuration of an inverted J and having a universal pivot member on an extended portion thereof, and

means securing the pivot members rotatably together for universal rotation relative to each other to permit universal rotation of said reel.
